UNITED STATES PATENT OFFICE.

ROBERT L. DORAN, OF CHICAGO, ILLINOIS.

HYDROCARBON-LAMP.

1,019,229.

Specification of Letters Patent.

Patented Mar. 5, 1912.

Application filed October 30, 1911. Serial No. 657,438.

To all whom it may concern:

Be it known that I, ROBERT L. DORAN, a citizen of the United States of America, and a resident of Chicago, county of Cook, 5 State of Illinois, have invented certain new and useful Improvements in Hydrocarbon-Lamps, of which the following is a specification.

The main objects of this invention are to 10 provide an improved form of hydrocarbon lamp having a main generator and a pilot-light generator connected to the fuel supply, and operative, independently of each other; to provide an improved arrangement of the 15 pilot-light generator and burner whereby it may be detached from the lamp without disturbing the main generator or interfering with its operation; and to provide improved means for insulating either or both genera- 20 tors from the lamp frame so as to prevent heating of the frame and avoid an unsteady delivery of fuel to either or both generators.

An illustrative embodiment of this invention is shown in the accompanying draw- 25 ings, in which—

Figure 1 is a side elevation of a supporting frame, main generator and burner, and pilot-light generator and burner constructed and arranged according to this invention. 30 Fig. 2 is a similar view with the pilot-light generator and burner removed. Fig. 3 is an enlarged sectional detail showing the construction of the connection between the main frame and the main and pilot-light genera- 35 tors.

In the construction shown in the drawings, the main frame 1 has connected thereto and supported thereon the main generator 2 and burner 3, the pilot-light generator 4, 40 and burner 5, and the globe support 6. The main generator 2 is supported on the frame 1 in a substantially horizontal position, and in substantial alinement with the open end of the mixer 7. The mixer 7 is supported 45 on the globe support 6 and carries the inverted burner 3, to which is attached a mantle 8. The flow of fuel to the generator 2 is controlled by the usual needle valve 9, at the outer end of which is connected the operating bar 10 from the ends of which depend the chains 11.

The pilot-light generator 4 is suspended 50 from the end of a tube 12 connected to the frame 1, and on which is supported the deflector 13 above the generator. The generator 4 is supported so as to locate the burner

5 directly above the main generator 2. The flow of fuel to the generator 4 is controlled by a needle valve 14, located in the fitting 15 below the connection of the frame 1 thereto, 60 and operated by a handle 16. The relative arrangement of the needle valve 14 and frame 1 on the fitting 15 provides separate passages by which the fuel is conducted to the two generators and which are separately 65 controlled by their respective valve mechanisms. The flow of gas from the generator 4 to the mixer 5^a is controlled by the usual needle valve operated by arm 5^b.

The generators 2 and 4 are each insulated 70 from the frame 1 and tube 12 by means of a plug or section 17 of comparatively low heat conductivity which is interposed between a cap 18 screwed onto the threaded nipple 19 or the end of the tube 12. The nipple 19 and tube 12 are each provided with internal conical shoulders 20 opposed to similar shoulders 21 on the caps 18 formed by apertures 22 extending through the end of the caps. The sections 17 are each provided 75 with conical shoulders which, when the caps 18 are firmly screwed up, engage the shoulders 20 and 21 whereby the sections are rigidly held in place. The sections 17 are each provided with a threaded aperture 23 adapt- 80 ed to receive the threaded end or nipple 24 formed on the generators 2 and 4, whereby 85 they are held in position.

In the hydrocarbon lamp of the usual construction, the supporting frame through 90 which the fuel is being conveyed and to which the generator is connected, often becomes heated to such an extent as to cause vaporization of the fuel therein in advance of the generator. Such vaporization of the 95 fuel causes a back pressure on the liquid fuel flowing to the generator, thereby resulting in an unequal delivery of fuel to the generator and producing a fluctuating light. This fault is overcome in the present construction by the use of the sections 17 for insulating the generator from the supporting frame.

The operation of the device shown in the drawings is as follows: If the lamp is used 105 as shown in Fig. 1, it will, of course, be necessary to preheat one or the other of the generators in order to start the lamp the first time, which may be accomplished by the use of any suitable torch—such, for example, as torch 25 shown in Fig. 2. After 110 the lamp is once started, the valve 14 is

opened to permit the flow of fuel through the tube 12 to the generator, whereupon it becomes vaporized and is directed to the burner 5 through the mixer 5^a. The flow of gas to the mixer is controlled by the usual needle valve operated by the handle 5^b, which is adjusted to maintain a constant flame directed onto the main generator 2 to keep it heated so that the lamp is always ready for instant use. During the burning of the lamp, the generator 2 is, of course, kept heated by the heat rising from the flame of the burner so as to cause the constant generation of gas, the flow of which into the mixer 7 is controlled by the needle valve 9. If it is desired to use the lamp without the pilot-light generator and burner, the supply of fuel thereto may be cut off by the valve 14, and the generator and burner detached from the tube 12 without disturbing any other part of the lamp, whereupon the lamp appears as shown in Fig. 2. When so used, it is necessary to preheat the generator each time before starting the lamp. This may be done by using a torch comprising a swab 25 secured to a wire 26 adapted to be hung over the generator in the position shown in dotted outline in Fig. 2. After the swab 25 has been saturated with alcohol or gasolene, it may be ignited and the generator heated to a temperature sufficient to commence the vaporization of the fuel therein for the

starting of the lamp. The insulating of the generators 2 and 4 from the frame 1 35 prevents heating of the frame 1 and thereby avoids any vaporization of the fuel in advance of its delivery to the generators, so that the gas is generated only by the generators and a steady delivery thereof to the 40 mixer is obtained, resulting in a steady light.

Although but one specific embodiment of this invention is herein shown and described, it will be understood that numerous details 45 of the construction shown may be altered or omitted without departing from the spirit of this invention, as defined by the following claim:

I. claim:—

A hydrocarbon lamp comprising a frame having a fuel inlet channel, a generator and burner connected with said frame and communicating with said fuel inlet channel, and a section of material of comparatively 55 low heat conductivity interposed between the connection of said burner and frame, so as to insulate said generator from said frame.

Signed at Chicago this 27th day of October 1911.

ROBERT L. DORAN.
